Primary Examiner—Elizabeth A Albert*Assistant Examiner*—Karen E Eldridge Powers(74) *Attorney, Agent, or Firm*—Fulbright & Jaworski, LLP(57) **CLAIM**

The ornamental design for a hat, as shown and described.

DESCRIPTION

FIG. 1 is a perspective view of a hat showing my new design;

FIG. 2 is a top view of the hat shown in FIG. 1; and,

FIG. 3 is a front view of the hat shown in FIG. 1.

The broken lines represent environmental structure that forms no part of the claimed design.
